FLAT PLATE PRINTING APPARATUS HAVING ACCURATE REGISTER

John J. Schaefer and Hugh B. Patrick, Louisville, Ky.,
assignors to Reynolds Metals Company, Richmond,
Va., a corporation of Delaware

Filed Nov. 22, 1960, Ser. No. 71,902

8 Claims. (Cl. 101—252)

This invention relates to printing apparatus of the flat plate type and more particularly to such an apparatus having an exceptionally accurate register. Although the invention is in no way limited to the printing of any one type of article, it is, however, especially well suited to the printing of sample patterns requiring a plurality of super-imposed impressions and during the printing of which no smudging occurs, a high fidelity of register is provided, and a uniform pressure is utilized in the printing of each impression.

Printed samples of this type may include, for example, wood grain patterns printed on panels, textile designs printed on cloth, or wall paper designs printed on paper. Thus, in contrast to printing practices involving apparatus having a high volume output and in which speed of printing is an essential factor, the present apparatus is intended for use in printing at a relatively slow rate, but with extreme accuracy. In this connection it will be understood that the term "accurate register" as used herein, connotes a register in the order of about 0.001 inch and which is impossible to achieve with many of the previously proposed forms of flat plate printing apparatus, as for example those forms in which the printing roll has gears in mesh with racks and wherein back-lash and wear contribute to lack of proper register, or with other forms wherein similar mechanical limitations are present.

An object of the invention is to provide a printing apparatus having an improved register of the printed article with the printing plate.

Another object is to provide an improved mechanism for raising and lowering a printing roll with respect to a printing plate and to an article to be printed.

Another object is to provide an improved table for establishing register between a printing plate and an article to be printed and which are disposed on the table.

A further object is to provide an improved carriage for a printing roll in a flat plate printing apparatus.

Other objects and advantages of the invention will become more apparent as the description proceeds and when considered in conjunction with the accompanying drawings in which:

FIG. 1 is a perspective view of the printing table showing a printing plate and an article to be printed in register thereon.

FIG. 2 is a sectional view of the table taken on line 2—2 of FIG. 1.

FIG. 3 is a plan view of a combined material holding and anti-smudge plate drawn to a smaller scale.

FIG. 4 is a side elevation view of one end of the table showing the roll and carriage in mounted position with respect thereto, and with the roll elevated from the printing plates, and with parts shown in dotted lines and parts omitted in the interest of clarity.

FIG. 5 is a partial sectional view, taken on line 5—5 of FIG. 4 and showing approximately one-half of the length of the roll.

FIG. 6 is side elevation view of the printing roll with parts in section.

FIG. 7 is an end elevation of the roll-indexing plate to a smaller scale.

FIG. 8 is a perspective view to a smaller scale of the yoke-back plate and yoke arms.

2

FIG. 9 is a detail view of the mounting both of a cradle in the carriage and the roll-indexing means, and

FIG. 10 is a detail sectional view through the roll-indexing means.

In accordance with the invention there is provided an elongated stationary flat table having one portion of its upper surface adapted to support a flat article to be printed and another portion of its upper surface spaced longitudinally from the first portion and adapted to support a flat printing plate. Means are provided for registering and holding each of the article and the plate with respect to the table in a longitudinal direction so as to provide initial transverse register lines on the article and the plate, and with which an initial register line on a rotatable printing roll may be brought into correspondence.

A carriage movable longitudinally of the table includes carriage positioning means for registration with the table at one station adjacent the initial register line on the plate and at another station adjacent the initial register line on the article. This carriage in turn supports the printing roll which is of the shafted type and which may rotate freely in a cradle mounted on the carriage when disengaged from a roll-indexing means mounted on the cradle, the roll being fixed against such rotation when engaged with that roll-indexing means. The roll-indexing means serves to establish the initial register line on the roll. The roll is selectively lifted and lowered with respect to the plate and article by a mechanism mounted on the carriage. In addition the carriage, when its carriage-positioning means is disengaged from the table, may be manually moved along the table by a simple pushing movement. The conjoint registration, indexing, lifting and lowering, and longitudinal movements of the several parts of the apparatus are all mutually coordinated to the end that a printing of the article with accurate register may be accomplished.

Referring now to FIG. 1, a stationary table having its upper surface at a convenient working height may include a first upper surface portion 10 adapted to support the inked flat printing plate 11 from which the impression is to be taken for transfer to the flat article 12 supported upon a second portion 13 of the table and longitudinally spaced from the first table portion. By means of legs 14, 15, 16 and 17 and suitable bracing, the table structure is rigidly assembled and as best seen in FIG. 2, includes an upper framing of parallel side angle members 18 and 19 joined at their ends to end angle members, one being shown at 20. The top flat surface of the table serving as a printing bed, may be formed of a pair of flat steel plates 21 and 22 attached to steel stringers 23, 24, and 24, 25 respectively and extending from one end angle member to the other and rigidly affixed thereto. Attached to the side angle member 19 and having a beveled track portion 26 extending upwardly therefrom and spaced outwardly from the side edge of the table, is an additional angle member 27 serving as a rail, and which is substantially coterminous with the angle member 19. Carriage stops 28 and 29 also are attached to the stringer 25 adjacent the respective ends of the same and in intersecting relation to the path of the extreme movement of the respective carriage wheels 54 and 53.

An array of conventional plate indexing pins, two of which are seen at 30 and 31, project in threaded relation through the bed plates 21 and 22 in the first surface portion of the table and serve as a registering means for printing plate 11, by engaging in apertures provided along the sides of that plate. The article to be printed, however, is preferably registered in its position on the second surface portion of the table by endwise confinement between elongated holding plates 32 and 33 extending transversely of the table. These plates may be of identical construction and as seen in FIG. 3, plate 32 may comprise a thin steel

member of about 16 gauge material having a length greater than the length of the printing roll and with a width of about four inches and sufficient to provide an antismudge function as later to be described. A pair of longitudinally extending recesses 34 and 35 are provided adjacent the ends of the holding plate and within which adjustable hold-down screws (not shown) are adapted to pass and to be fastened into threaded corresponding apertures in the upper surfaces of the respective bed plates 21 and 22.

Referring now to FIGS. 1, 4 and 5, a pair of identical elongated carriage register bars 40 and 41 having a suitable conformation for nesting against the outer side of the track member 27 are provided and include a pair of elongated slots 42 and 43 and a centrally located carriage-positioning aperture 44 (FIG. 5). The upright side portion of the track member contains an array of tapped holes 45 therethrough in the vicinity of the forwardmost positions to be occupied on the table by the plate and the article. By means of a register adjustment knob having a threaded pin attached thereto for engagement with the tapped holes 45, one such knob and pin as seen at 46 and 47 being provided for each of the slots in a register bar, the register bars may be positioned to bring their roll-positioning apertures into a fixed position bearing a predetermined relation to the initial register lines of the plate and article when those bars are clamped against the track member.

As a feature of the invention, a smoothly movable carriage is provided for supporting not only the printing roll but also the entire mechanism used for raising and lowering that roll, and this carriage comprises a right side plate 50 and a left side plate 51. Adjacent the lower corners of these side plates, shaft apertures are provided for receiving shafts on which a pair of guide rollers are mounted for the left side plate, one being shown at 52, and a pair of guide wheels 53 and 54 are mounted for the right side plate. The rollers have a cylindrical periphery and roll in contact with the flat bed plate 21 above the stringer 23, and the wheels have a grooved periphery and roll in contact with the bevelled edge 26 of the rail member 27, each of the rollers and wheels having conventional friction-reducing bearings on their shafts. The grooved wheels in engagement with the bevelled edge of the track serve to prevent any side sway of the carriage as it moves along the track. Extending between the side plates is a plurality of spacing rods rigidly attached thereto and serving to provide rigidity to the structure, an end of two such rods being seen at 55 and 56.

Rigidly attached to the outer surface of the right side plate is a bracket 57 extending downwardly in overlapping relation to the register bars. Adjacent its lower end this bracket supports a carriage-positioning pin 58 engageable in the carriage-positioning aperture 44 when moved toward the carriage and serving to lock the carriage to the register bar, and disengageable from that aperture when moved away from the carriage and serving to unlock the carriage from its register bar.

Passing now to FIGS. 6 and 7, the printing roll preferably comprises an aluminum alloy extrusion in the form of a hollow cylinder 60 and includes a shaft having ends 61 and 62 projecting from the ends of the roll, and serving as an axle for the roll. Gudgeons 63 and 64 serve to enclose the ends of the cylinder and provide space for conventional friction-reducing bearings 65 and 66 supporting the shaft within the cylinder and permitting ease of rotation of the cylinder upon that shaft. These bearings are held in place by suitable set collars 67 and 68 and adjacent the ends of the shaft additional set collars 69 and 70 also are provided for a purpose later to be described. The peripheral surface of the roll preferably is provided with a layer 120 of rubber, gelatine, or the like, about 0.75 inch thick and adapted to pick up the inked impression from the printing plate 11 and to transfer the same to the article 12. The printing plate preferably is an engraved metallic plate and the cells of the same may range between 0 and 40-45 microns in depth. As later to be

described, the weight of the roll alone is employed to furnish the pressure during printing and since a substantially frictionless movement of the roll occurs, a substantially constant printing pressure is applied at all times.

At the right hand end of the roll an index plate 71 is attached thereto in surrounding relation to the shaft and includes a number of index slots here shown at A, B, C, and D, concentrically disposed with respect to the axis of the roll. Formed in each of the carriage side plates is a slot extending normally to the plane of the table top and within which a cradle member is adapted to reciprocate with a close fit, the cradle member 72 for the right hand end of the roll being seen in FIGS. 4 and 9. These cradle members may have shoulders encompassing the edges of the slotted sides of the carriage so that all movement of the cradle members is reciprocatory. These cradle members include an upwardly directed open slot 73 into which the respective shaft ends and axles are positioned and as will be understood, the roll and its shaft may be manually raised from these cradles when the roll is to be cleaned or replaced and may be placed in these cradles when a printing operation is to be conducted. The right hand cradle 72 has rigidly attached to its bottom a roll index pin housing 74 with a horizontally projecting bushing 75 including a securing pin slot 76 on its outer face (FIG. 5). An aperture extends through both the bushing and housing for containing a longitudinally movable roll index pin 77 at the distal end of which is a locking member 78 engageable with a close fit in any chosen one of the several index slots of the roll. A register adjustment knob 79 is attached to the index pin 77 at its outer end and rigidly affixed to the index pin, intermediate its ends is a transversely extending securing pin 80. This securing pin fits within the slot 76 of the bushing, when the locking member 78 is in engagement with the index slots of the roll and rests against the outer face of that bushing when the roll is free to rotate on its shaft. A compression spring 121 is interposed between the locking member 78 and the inner surface of the housing 74 and biases the locking member toward the roll index plate.

The slot in the right hand carriage plate has an inwardly directed shoulder 81 upon which the lower edge of the cradle 72 bottoms when the roll is fully lowered in the manner later to be explained, and sufficient space is provided below this shoulder to accommodate the housing 74 when the roll is so lowered. In the corresponding left hand carriage plate, the bottom of the slot for that cradle corresponds to the same elevation above the table top as the shoulder 81 with the result that as the roll is raised or lowered in its cradles, the axis of such roll remains at all times parallel to plane of the table top. It will be understood that when the respective cradles bottom in their slots, the entire weight of the roll and its shaft is then transmitted to the roll covering in contact with the printed place of the article being printed. Each of the cradles has an inwardly projecting cradle operating pin threaded into the cradle and rigidly secured thereto as by a nut engaging against the outer surface of the cradle, the pin having a finished cylindrical head for engagement with a pivoted yoke next to be described. As seen in FIGS. 5 and 9, the pin 82 for the right hand cradle has a head 83 and is secured by a nut 84.

For the purpose of raising and lowering each cradle in unison, a double yoke comprising a back plate 85 having 65 attached thereto at its ends a pair of yoke arms 86 and 87 is provided. Each of these arms is pivoted intermediate its ends upon a stationary pin fastened in the respective side walls of the carriage and passing through the respective apertures 88 and 89 in these yoke arms. In addition the forward ends of the yoke arms contain open slots 90 and 91, in which the respective cradle operating pins are engaged at all times. The engagement of the right hand yoke arm with the operating pin 82-83 is best seen in FIGS. 4 and 5.

Attached to the rear of the yoke back plate adjacent its

center, is a pair of spaced brackets 92 and 93 having a yoke elevation bar 94 extending therebetween and resting in engagement at all times within an open slot 95 of a yoke actuating nut 96. This nut is interiorly threaded and is in threaded engagement at all times with an elongated downwardly projecting yoke actuating screw 97. At the upper end, this screw is rotatably held in place by means of a set collar 98 bearing against the outer surface of a heavy suspension member 99 extending across the top of the carriage and attached to the top edges of the respective carriage side walls near the rearmost portion thereof.

Rigidly affixed to the underside of the suspension member on opposite sides of, and rearwardly of, the yoke screw is a pair of shaft support blocks 100 and 101 having an aperture therethrough receiving bushings 102 and 103 within which extends an elevating shaft 104.

A helical gear 105 is keyed to the elevating shaft between the bushings and is confined by suitable thrust bearings 106 and 107 interposed between that gear and the respective shaft support blocks. In mesh with helical gear 105 at all times, is a second helical gear 108 keyed to the screw 97 and confined against upward movement by a thrust bearing 109. The inner end of the elevating shaft 104 terminates slightly beyond the shaft support block 101 and the other end of that shaft projects through a bushing 110 mounted in the right hand side wall 50 of the carriage. A suitable handwheel 111 is affixed to the outer end of the shaft 104 and serves to actuate the entire lifting and lowering mechanism for the roll.

With the foregoing description of one suitable arrangement for carrying out the invention in mind, the several objects and advantages of that invention will now become apparent when considered in connection with the following described operation.

Having an inked printing plate 11 in proper register with respect to the first carriage register bar 41 and an article 12 in proper register with respect to the second carriage register bar 40, it will be apparent that when the carriage is engaged by means of its carriage positioning pin with either of those register bars and when the roll is brought into contact with either the plate or the article, a predetermined line lengthwise of that roll serving as its initial register line will then coincide with a predetermined transverse line on either of the plate or the article and serving as initial register lines therefor. Each of the structural features of the apparatus is directed toward this useful end result and the manufacturing tolerances and functioning of the movable parts is such that accuracy of register of those initial lines may be in the order of about 0.001 inch.

With the roll surface 120 in clean condition, the carriage-positioning pin 58 engaged with register bar 41, the roll in elevated position, and the roll index pin 77 in engagement with an index slot, for example slot A; the operator then turns hand wheel 111 and the yoke assembly pivots upon its stationary pins and lowers the pins attached to the respective cradle members within which the axles 61 and 62 of the roll are resting. Each of these cradle members are confined to movement in a predetermined plane and the angularity of the pivoted yoke in no way influences the movement of those cradles. However, since the index pin 77 itself is carried by the extension 74 of the cradle 72, no rotational movement of the roll on its own axis can occur while it is so locked by that index pin. Accordingly, the roll comes to rest in contact with the upper surface of plate 11 with a coinciding of the respective initial register lines of these two elements. The pressure exerted by the roll upon that plate moreover is that afforded solely by the weight of the roll itself.

Having thus brought the roll into accurately registered position to take up an impression, the operator then moves the roll index pin outwardly to its second position, freeing the roll to rotate, and then withdraws the carriage-positioning pin 58. After this, the carriage is moved forward

by means of its rollers and wheels until the desired impression has been taken from plate 11, the roll meanwhile rotating freely upon the bearings 65 and 66 thereof and the axles remaining stationary in the respective cradles. The set collars 69 and 70 which engage against the outer surface of the carriage side walls serve to prevent any accidental axial shifting of the roll at any time during use. At the conclusion of the carriage movement, the line of contact of the roll with plate 11 may be for example adjacent the index slot D of that roll. At this time the carriage is stopped and handwheel 111 is actuated to lift the cradles and to raise the roll. Having lifted the roll from contact with plate 11, the operator then manually turns the roll to bring index slot A again into position to be engaged by the index pin 77, and when this pin is so engaged in slot A the carriage is then moved to its printing station.

At this station, the carriage-positioning pin 58 is engaged with the second register bar 40 thus to relate the initial register line on the roll to the initial register line on the article 12. Thereafter, the operator again turns the hand wheel to lower the roll into contact with the article 12, moves the roll index pin 77 outwardly to its second position, and withdraws the carriage-positioning pin 58. Since the thicknesses of both the plate and the article will be equal, shims being employed whenever necessary to accomplish this condition, the roll accordingly will rest upon article 12 with the same pressure with which it rested on plate 11. The operator then moves the carriage forward and the inked impression which the roll took from the plate is then transferred with fidelity of reproduction to the article.

Following this transfer of the impression, the roll again is raised from the table surface and is detached from the carriage. This detachment is readily conducted by merely lifting the axles of the roll from the slots in the cradle members. Various procedures may now be followed after the described first printing impression has been finished. For example, a second printing plate 11 having one initial register line corresponding to the same initial register line of the previously used plate may now be placed in position and covered with ink of a different color as when multi-color inks are to be used on the finished article, or may be a differently engraved plate using the same color of ink as before. A clean roll is then disposed in the carriage cradles and is registered with the carriage, the carriage in turn being registered with the first register bar 41, after which the same sequence of steps above described are carried out to superimpose the second printing impression upon the first such impression, and with a standard printing pressure being used in both printings. As many such impressions as desired may be employed in the production of the printed article with assurance that accurate register will be present and that a uniform printing pressure will always be used.

Various useful features of the apparatus will be apparent to those skilled in the art, among which is the ease of avoiding a smudging of the article as the roll starts to move thereover. This may be accomplished by providing the holding plate 32 with sufficient width so that the initial register line of the roll may coincide with an initial register line on such a holding plate rather than on the article itself. In this event, the roll is in motion before its surface touches the edge of such article and any tendency to squeeze ink when the roll reaches its lowermost position, takes place on the holding plate rather than on the article itself. When so employed the holding plate itself is cleaned after each printing impression is finished.

Although the roll indexing has been described with respect to slot A constituting an initial register line region, it will be obvious that any of the other index slots may be so employed and in fact it is desirable to use such slots in sequence to compensate for any wear of the roll or setting of the roll covering.

The actuation of the yoke mechanism also contributes to the quality of the printing since each yoke arm lowers and raises the axles of the roll in unison and thus both extremities of the roll touch the plate and article uniformly. In addition, since the body of the roll rotates freely upon the bearings in the gudgeons, no frictional factors which might be present if the axles themselves were attached fixedly to the roll body, need be compensated for.

Having then described the invention and having shown a preferred form of structure for carrying out the operation of the same, it will be apparent that various changes and modifications may be made in the apparatus without departing from the invention. It therefore, is intended in the appended claims to cover all such changes and modifications as may fall within the true spirit and scope of the invention.

What is claimed is:

1. A printing apparatus comprising in combination, a flat table having a first portion adapted to support a flat inked plate and a second portion adapted to support a flat article to be printed, a plate registering means and an article registering means for establishing initial register lines transversely of said plate and of said article respectively, first and second carriage register means supported upon said table and cooperating with said plate registering means and said article registering means respectively, a carriage mounted upon said table for movement therewith, carriage-positioning means for releasably connecting said carriage to a selected one of said first and second carriage register means, a shafted printing roll removably mounted upon said carriage and having an axle projecting from each end thereof, means for selectively lifting and lowering said roll with respect to said table and including cradles mounted in said carriage and supporting the respective axle portions of said roll, roll-indexing means carried by one of said cradles and adapted to connect said roll rigidly to said carriage while in a first position and to permit said roll to rotate with respect to said carriage while in a second and disconnecting position, said roll-indexing means while in said first position serving to establish an initial register line lengthwise of said roll and in correlation to the initial register lines of said plate and said article, and means for moving said roll-indexing means to said disconnecting position thereof, thereby to permit said roll to rotate with respect to said carriage during the printing movement of said carriage along said plate and said article.

2. A printing apparatus comprising in combination a flat table having a first portion adapted to support a flat inked plate and a second portion adapted to support a flat article to be printed, the upper surface of each of said plate and said article being at equal elevation above said table, a plate registering means and an article registering means for establishing initial register lines transversely of said plate and of said article respectively, first and second carriage register means supported upon said table and cooperating with said plate registering means and said article registering means respectively, a carriage mounted upon said table for movement therewith, carriage-positioning means for releasably connecting said carriage to a selected one of said first and second carriage register means, a shafted printing roll removably mounted upon said carriage and having an axle projecting from said end thereof, means for selectively lifting and lowering said roll with respect to said table and including cradles mounted in said carriage and supporting the respective axle portions of said roll, said cradles being movable downwardly sufficiently to permit the roll to rest its entire weight upon said plate and said article respectively and to provide a constant printing pressure, roll-indexing means carried by one of said cradles and adapted

5
10
15

to connect said roll rigidly to said carriage while in a first position and to permit said roll to rotate with respect to said carriage while in a second and disconnecting position, said roll-indexing means while in said first position serving to establish an initial register line lengthwise of said roll and in correlation to the initial register lines of said plate and said article, and means for moving said roll-indexing means to said disconnecting position thereof, thereby to permit said roll to rotate with respect to said carriage during the printing movement of said carriage along said plate and said article.

3. In a printing apparatus having a stationary table, a flat printing plate supported on said table, a flat article to be printed supported on said table, a carriage movable along said table, a shafted printing roll mounted on said carriage, and means for raising and lowering said roll with respect to said plate and said article; the improvement comprising a track affixed to said table along one side thereof, a first carriage register member attached to said track adjacent one end of said plate, a second carriage register member attached to said track adjacent a corresponding end of said article, said carriage having side walls spaced transversely of said table, means attached to one of said side walls for supporting said carriage for movement along said table, wheel means attached to the other of said side walls and movable along said track for supporting said carriage for movement along said table, and carriage-positioning means selectively engageable with either of said carriage register members.

4. Apparatus as defined in claim 3 wherein said carriage side walls include slots extending in a generally vertical direction, and said means for raising and lowering said roll includes cradle members positioned in said slots and supporting the respective ends of the roll shaft.

5. Apparatus as defined in claim 4 wherein said cradle members while in their lowermost positions in said slots permit the entire weight of said roll and shaft to be supported by said printing plate and said article respectively.

6. In a printing apparatus having a stationary table, a flat printing plate supported on said table, a carriage movable along said table, and a shafted printing roll supported upon said carriage; the improvement comprising means mounted upon said carriage for raising and lowering said roll with respect to said plate and including spaced cradle members slidably mounted on said carriage and supporting the respective shaft ends of said roll, spaced yoke arms pivotably mounted upon said carriage and movably attached adjacent one end to the respective cradle members, and yoke-actuating means mounted upon said carriage for simultaneously actuating said yoke arms thereby to raise each end of said roll uniformly away from said plate as said yoke-actuating means is moved in the direction to raise said cradles and to lower each end of said roll uniformly toward said plate as said yoke-actuating means is moved in the direction to lower said cradle members.

7. Apparatus as defined in claim 6 wherein said yoke-actuating means includes a single rotatable screw, means connecting said screw to said yoke arms, and means for rotating said screw.

8. Apparatus as defined in claim 7 wherein said screw is mounted in a generally vertical position and spaced at approximately equal distances from the ends of said roll.
